UNITED STATES PATENT OFFICE.

VERNON B. DAWSON, OF BRIDGETON, NEW JERSEY.

COMBINED ERASER-HOLDER AND POINT-PROTECTOR FOR PENCILS.

1,353,896.

Specification of Letters Patent. Patented Sept. 28, 1920.

Application filed May 9, 1917. Serial No. 167,534.

To all whom it may concern:

Be it known that I, VERNON B. DAWSON, a citizen of the United States, residing at Bridgeton, in the county of Cumberland, 5 State of New Jersey, have invented certain new and useful Improvements in Combined Eraser-Holders and Point-Protectors for Pencils; and I do hereby declare the following to be a full, clear, and exact description 10 of the invention, such as will enable others skilled in the art to which it appertains to make and use the same.

This invention is an improvement in pencil attachments and has particular reference to a combined eraser holder and point protector.

An object of the invention is to prolong the usefulness of a pencil eraser by providing an improved holder therefor, a portion 20 of which is adjustable to uncover or expose the outer or operative end thereof as the same wears away.

Another object is to provide a device of this character which is simple in construction, easy to manufacture and effective in carrying out the purpose for which it is designed.

The inventive idea involved is capable of receiving a variety of mechanical expressions, one of which, for the purpose of illustrating the invention, is shown in the accompanying drawing, wherein:

Figure 1 is a side elevation of the attachment showing the same applied to a pencil.

Fig. 2 is a longitudinal sectional view.

Fig. 3. is a transverse section on the line 3—3 of Fig. 1.

Referring more particularly to the accompanying drawing, the numeral 5 indicates a pencil upon either end of which is adapted to be mounted the eraser holding member generally indicated by the numeral 6 and preferably formed of an elongated, open ended tube made of any desired material 40 and having one end split as indicated at 7 to provide the resilient lips 8 which are adapted to engage over the pencil and tightly grip the same to prevent accidental displacement. Intermediate the ends of the member 6 the 45 same is provided with a fixed bead 9 employed to facilitate the adjustment and removal of the member upon and from the pencil. The end of the holding tube 6 opposite that which is split has mounted thereon 50 in the rubber eraser 10 which is preferably

made the same shape and cross section as the tube 6 in order that its inner end may be forced for a short distance into such member to tightly fit the same. By reason of the present invention it is possible to greatly increase the length of the eraser 10 and thereby prolong the usefulness thereof and avoid the necessity of constantly replacing the same, as well as obviate having a pencil without an eraser, as commonly occurs, 60 owing to the fact that the eraser usually wears out before the lead.

It will be obvious, from the drawing, that a considerable portion of the length of the eraser projects beyond the end of the tube 6 70 in which it is mounted and in order that the projecting part of said eraser may be held in a comparatively rigid position, use is made of a sleeve 11 preferably of the same formation in cross section as the tube 6 and of a 75 diameter slightly greater than the latter so that it will fit upon and frictionally engage the same and considerable pressure will be necessary to adjust the sleeve longitudinally. In order to facilitate this adjustment the 80 sleeve is provided with a fixed bead 12 intermediate its ends which may be engaged by the fingers of the operator to provide a suitable grip. When the sleeve 11 is in the position shown in Figs. 1 and 2, only a comparatively small portion of the outer or operative end of the eraser 10 projects beyond the outer end of said sleeve so that the eraser will be held in a comparatively rigid position, and as the end of the eraser is worn the 85 sleeve 11 may be adjusted inwardly upon the rubber and along the tube 6 until the inner end thereof contacts the fixed bead 9 at which time the eraser will yet project 90 slightly beyond the end of said tube 6. The remaining portion of the eraser may then be extracted and replaced by a new eraser.

It will thus be seen from the foregoing description that the attachment may be readily mounted upon either end of a pencil in order that the point may be protected when not in use and that when the usefulness of the eraser is exhausted the attachment need not be thrown away but need only having another eraser mounted therein and can 100 be used on other pencils.

What is claimed is:—

An improved eraser holder comprising a tube split at its lower end to receive a pencil and having an exterior bead at its mid- 110

length, a rubber eraser having one end held in the upper end of the tube, and an internally smooth sleeve telescoped on the tube and slidably inclosing the projecting portion of the rubber, the sleeve being longer than the distance from the upper end of said tube to its bead.

In testimony whereof I affix my signature in the presence of two witnesses.

VERNON B. DAWSON.
